(57) **CLAIM**

We claim, the ornamental design for a game pad for a cellular phone, as shown and described.

DESCRIPTION

FIG. 1 is a top and front perspective view of a game pad for a cellular phone, showing our new design;

FIG. 2 is a front elevational view thereof;

FIG. 3 is a rear elevational view thereof;

FIG. 4 is a left side elevational view thereof, the right side is a mirror image of the left side;

FIG. 5 is a top elevational view thereof;

FIG. 6 is a bottom elevational view thereof; and,

FIG. 7 is a front perspective view thereof, showing the game pad for a cellular phone being connected to a cellular phone. The broken line showing of environment in FIG. 7 is for illustrative purposes only and forms no part of the claimed design.
